UNITED STATES PATENT OFFICE

JOHN DOPYERA, OF LOS ANGELES, CALIFORNIA

STRINGED MUSICAL INSTRUMENT

Application filed March 23, 1928. Serial No. 265,254.

This invention relates in general to stringed musical instruments, and more particularly harps, and the main object is to provide in a harp of usual character a plurality of diaphragms arranged for connection with the strings of the instrument and serving as resonators, by means of which the tones produced by vibrating the strings will be substantially amplified.

10 Another object is to provide in a harp a plurality of metallic diaphragms or resonators of the general character and for the same purpose as those employed in the instrument of my invention shown in my pending application for Letters Patent in the United States filed Oct. 12, 1926, Serial Number 141,115.

15 It is contemplated in the present invention to provide a plurality of metallic diaphragms or resonators in the sound box of the harp and to arrange the same singly or in pairs throughout the length thereof and to connect them with the strings of the instrument at 20 intervals in such a manner that the volume 25 of the instrument will be substantially increased.

In a harp or other stringed musical instrument to which the metallic diaphragms or resonators are applied for the purpose of 30 amplification, it is desirable to provide diaphragms of conical form and of metal, preferably aluminum, which is so thin that it may be readily flexed or indented at local 35 points by pressure thereon.

35 With these and other objects in view, I have shown a preferred form of invention in the accompanying drawings, in which:

40 Fig. 1 is a side elevation of a well known type of harp to which my invention is applied.

45 Fig. 2 is a fragmentary perspective view of the same showing a portion of the sound box with the resonators mounted thereon and connected with the strings of the instrument.

Fig. 3 is an elevation of the sound box with the outer cover removed and showing the complete assembly of resonators.

50 Fig. 4 is a section of the same on line 4—4 of Fig. 5.

Fig. 5 is a sectional elevation of the sound box.

Fig. 6 is a fragmentary section of the sound box showing a preferred method of forming and mounting the resonators.

Now referring to Fig. 1, in which a typical form of harp is shown, such an instrument comprises a base B, a sound box C inclined upwardly at an angle from the base, a standard D forwardly of the sound box and an arch A connecting the upper ends of the sound box and the standard. The sound box C has a compartment C' formed therewithin and surrounded by an arcuate metallic casing which is provided with an opening O in the rear side thereof. The front of the sound box has a shallow compartment E formed between a front cover-plate e and a partition e', as shown in Fig. 5. The strings S, S etc. of the instrument are attached in the usual manner to the arch A at their upper ends and extend through an elongated slot 2 in the cover-plate e and through bayonet slots 3, 3 etc. in an angle bar F, which is positioned intermediate between the plate e and the partition e'. The lower ends of the strings extend through said partition and are secured in the usual manner as shown in Fig. 5.

I provide on the sides of and below the bar F a series of metallic diaphragms G, G etc. and G', G' etc. respectively. Said diaphragms are of conical form and are mounted with the bases of the cones on the outer sides of the partition e'. The diaphragms are arranged in pairs transversely and the apices of the cones of each pair are engaged by transversely disposed bridges H, H etc. which overlie the diaphragms and underlie the bar F, as shown in Fig. 4. Thus it will be observed that when the strings S are taut the lower portions S' of the strings between the bar F and the partition e' will be bent at angles with respect to the upper portions of the strings so that the strings will frictionally engage the ends of the bayonet slots 3 in the bar F and the vibration from such strings will be communicated through the bar F and the bridges H to the resonators G and G' when the instrument is played.

It will be noted by reference to Fig. 3 that

the sound box C of the instrument gradually decreases in area upwardly as the pitch of the strings increases and I prefer to graduate the size of the diaphragms G and G' correspondingly, as shown in Fig. 3.

I prefer to form the resonators G and G' with beads 4 internally of the edges 5 thereof in order to increase the vibrational qualities of the diaphragms, altho they may be otherwise formed as shown in the drawings with more or less satisfactory results.

The details of structure and the manner of attaching the diaphragms to the partition e' are not material to this invention.

The structure shown and described can obviously be applied to any instrument after the same has been constructed merely by adding the resonators G and G' and the bridges H. It is important, of course, that apertures g, g etc. be provided in the partition e' beneath the diaphragms so that the sound may be readily conducted through the partition e' into the sound box. The opening O in the sound box casing C serves the purpose of conducting the sound outwardly from the sound box.

The use and operation of my improvements in connection with a harp will be readily appreciated by those familiar with the manufacture and use of such instruments, and I conceive it to be possible to modify the structure to meet demands of use within the scope of the appended claims without departing from the spirit of my invention.

What I claim is:

1. A harp comprising a frame including a sound box provided with an inner partition and a cover-plate spaced therefrom, said cover-plate having a slot therein and said partition having a plurality of apertures, a plurality of strings held in tension on said frame extending through the slot in said cover-plate and attached at their lower ends to said partition, means below said cover-plate for engaging and holding the strings in tension, a plurality of metallic conical diaphragms mounted on and over the openings in said partition and connected at their apices with said tensioning means while communicating the vibrations from the strings to the diaphragms.

2. A harp comprising a frame including a sound box, provided with an inner partition and a cover-plate spaced therefrom, said cover-plate having a slot therein, a plurality of strings held in tension on said frame and extending thru the slot in the cover-plate, means internally of the cover-plate for engaging and holding the strings in tension, and a plurality of metallic diaphragms mounted on said partition and connected with said tensioning means for communicating the vibrations from the strings to the diaphragms.

3. A harp comprising a frame including a

sound box having an inner partition and a cover-plate spaced therefrom, a plurality of strings held in tension on said frame and extending thru said cover-plate, a plurality of resonators mounted on said partition, bridges connecting sets of said resonators, and a bar engaging said strings and said bridges for communicating the vibrations from the strings to the resonators.

4. A harp comprising a frame including a sound box, a partition and a cover-plate spaced apart on said sound box, strings held in tension on said frame extended thru said cover-plate and attached to said partition, a plurality of resonators mounted on said partition, bridges connecting sets of said resonators, and a bar engaging said bridges and having recesses for engaging said strings whereby the vibrations from the strings may be communicated to the resonators.

5. A harp comprising a frame having a standard and a sound box inclined upwardly from the base of the frame, a head piece connecting the upper extremities of said sound box and said standard, a partition in said sound box, a cover-plate on the sound box spaced therefrom, strings attached at opposite extremities to said head piece and to said partition, a plurality of diaphragms mounted on said partition, and means connecting said diaphragms and said strings for communicating the vibrations from the strings to the diaphragms.
